Primary Examiner — Nicole C Shiflet*(74) Attorney, Agent, or Firm* — Yee & Associates, P.C.(57) CLAIM

The ornamental design for a display screen with an animated graphical user interface, as shown and described.

DESCRIPTION

FIG. 1 is a front view of a first image in a sequence for a display screen with an animated graphical user interface; FIG. 2 is a front view of a second image thereof; FIG. 3 is a front view of a third image thereof; FIG. 4 is a front view of a fourth image thereof; and, FIG. 5 is a front view of a fifth image thereof.

The broken lines illustrate the display screen and portions of the graphical user interface and form no part of the claimed design.

The appearance of the animated image sequentially transitions between the images shown in FIGS. 1 through 5. The process or period in which one image transitions to another image forms no part of the claimed design.
